UNITED STATES PATENT OFFICE.

FREDERICK G. KEYES, OF EAST ORANGE, NEW JERSEY, ASSIGNEE TO COOPER HEWITT ELECTRIC COMPANY, OF HOBOKEN, NEW JERSEY, A CORPORATION OF NEW JERSEY.

TERMINAL CONNECTION FOR LAMP-FILAMENTS.

1,161,828.

Specification of Letters Patent. Patented Nov. 23, 1915.

Application filed November 6, 1912. Serial No. 872,366.

To all whom it may concern:

Be it known that I, FREDERICK G. KEYES, a citizen of the United States, and resident of East Orange, county of Essex, State of New Jersey, have invented certain new and useful Improvements in Terminal Connections for Lamp-Filaments, of which the following is a specification:

The present invention has to do more particularly with heavy metallic filaments, generally of tungsten, such as I have made use of in practice and such as are covered by various applications of mine for Letters Patent of the United States,—as, for example, my applications Nos. 811,002 and 811,002, filed January 8th, 1914. In using such filaments the problem of making the terminal connections therefor with the leads of the lamp is a serious one. The devices shown and described herein have been found to be efficient for the purpose and the present specification is designed to enable others skilled in the art to make and use these improvements.

25 The invention is illustrated in the accompanying drawings in which—

Figure 1 is a vertical section through the major portion of a lamp embodying my invention; Fig. 2 is a detail view of one embodiment of my invention and Fig. 3 illustrates a modification.

Since the invention is especially concerned with the terminal connections, it is only necessary to speak briefly of the other elements of the lamp.

In the first figure of the drawings, 1 is a lamp globe and 2 a reduced tubular extension thereof. Within a reentrant portion 3 of the extension are mounted seals 4, 4, within which are wires 51, 51 soldered or otherwise connected to lead rods or wires 5, 5, with interposed spirals, 6, 6, for preventing the application of too much strain directly to the seals. The lead wires, 5, 5, pass through a disk 7 of some suitable material such as aluminum, being insulated therefrom by sleeves 8, 8, and extending downward below the disk and being connected at the bottom by screw connections or otherwise with metallic blocks or plates, 9, 9. The disk 7 is supported upon a shoulder 10 extending around the interior of the tubular

portion 3 near the mouth thereof and the said disk also supports wires 11, 11, which at their lower ends hold up the filament at 55 various points to prevent too great sagging.

The filament itself (shown at 50) is usually wound in the form of a spiral and is so shown in Fig. 1 hereof. The problem of connecting the ends of the spiral with the blocks or plates 9, 9, is that which concerns us in the present instance.

Referring to Fig. 2, the part is shown as provided with an opening or perforation 12, in the form of a truncated cone, into which a wedge-shaped plug 13 may be pressed. Around the plug I wind a spiral 14 of bare wire (this may be tungsten wire) and I run the two ends of the spiral to a joint 15 which connects with one of the terminals of the main spiral filament 50. The joint 15 may be a welded joint, as shown. With the same arrangement at the opposite end of the filament an excellent connection is found between the filament and the block or plate 9. This is aided by the fact that owing to its wedge shape the plug 13 tends to create a very intimate connection between the plug and the spiral surrounding it and also between the coils of the spiral itself. The block 9 is preferably an iron block and the plug is a tapered pin of tungsten or molybdenum.

In Fig. 3 the joint 15 is superseded by a short spiral 16 of wire extending from the part which surrounds the plug 13, the proportions being such that the spiral 16 will enter the main spiral 50 and the two spirals may be screwed together and form a close and intimate connection.

It is obvious that instead of using joints between the part 14 and the filament ends, the filament itself may be made long enough to be wound around the block.

I claim as my invention:

1. In a filament lamp, a lead terminating in a metallic block having a perforation, in combination with a plug for entering the said perforation, a coil of wire closely surrounding the said plug and a main lamp filament and means for physically and electrically connecting the said filament with the ends of the said coil.
2. In a filament lamp, a lead terminating

2

in a metallic block having a perforation, in combination with a plug for entering the said perforation, a coil of wire closely surrounding the said plug and a main lamp filament and means for physically and electrically connecting the end of said filament with the ends of the said coil.

Signed at New York, in the county of New York and State of New York, this 4th day of November, A. D. 1914.

FREDERICK G. KEYES.
